UNITED STATES PATENT OFFICE.

CHARLES A. TURNER, OF BROOKLYN, NEW YORK.

DESIGN FOR A HORSE-BLANKET.

SPECIFICATION forming part of Design No. 20,539, dated March 3, 1891.

Application filed September 27, 1890. Serial No. 366,369. Term of patent 7 years.

To all whom it may concern:

Be it known that I, CHARLES A. TURNER, a citizen of the United States, residing at the city of Brooklyn, in the county of Kings and

5 State of New York, have invented and produced a new and original Design for Blanket Material Specially Adapted for Horse-Blankets, of which the following is a specification, reference being had to the accompanying drawings, forming part thereof.

Figure 1 is a side elevation of a horse-blanket, showing my design; and Fig. 2, a similar view of a portion of the blanket, in which the bands or bars forming part of the design 15 are enlarged and somewhat modified in character.

The leading feature of my design consists in alternate double and triple stripes or bands C D of one general color on a fabric of another general contrasting color, thus forming 20 overlapping squares A B, the letters of refer-

ence on the drawings being placed at the center of the respective squares. The stripes or bands C D run both lengthwise and crosswise of the material.

25

In Fig. 1 the stripes or bands are represented as solid, while in Fig. 2 they are formed of slanting lines or threads.

What I claim is—

The design for blanket fabrics herein shown 30 and described, consisting of alternate double and triple stripes or bands of one general color on a fabric of another general or contrasting color and forming overlapping squares A B.

35

In testimony whereof I have signed my name to this specification in the presence of two subscribing witnesses.

CHAS. A. TURNER.
